CAM TYPE OF BENCH VISE

William Milus, Detroit, Mich.

Application April 15, 1952, Serial No. 282,417

2 Claims. (Cl. 81—19)

1

The purpose of my invention is to provide a vise in which an object may be clamped quickly in a desired position and in which, thereupon, by means incorporated in said vise, a powerful gripping action is obtained to secure the object against displacement.

A further object of my invention is to adapt the vise for a special task of firmly clamping pipes, for which object certain elements of the vise have been suitably modified.

I shall now describe my vise with reference to the accompanying drawings in which:

Fig. 1 is a side elevational view of my vise;

Fig. 2 is a front elevational view thereof;

Fig. 3 is a sectional view on line 3—3 of Fig. 2;

Fig. 4 is a sectional view on line 4—4 of Fig. 3;

Fig. 5 is a side elevational view of a modified species of my vise;

Fig. 6 is a vertical sectional view of said vise;

Fig. 7 is a horizontal sectional view of the vise on line 7—7 of Fig. 5;

Fig. 8 is a perspective view of a cam used in both forms of my vise and a fragmentary view of an element actuated by said cam;

Fig. 9 is a sectional view on line 9—9 of Fig. 5.

Similar numerals refer to similar parts throughout the several views.

The vise includes a stationary member generally indicated by numeral 10, which member may be best made of cast metal. Adapted to be mounted on a bench or a similar horizontal support, the vise is provided with a base 11 which may be bolted to said support or secured thereto by a clamp which is not shown.

The upper portion of member 10 is formed with a jaw 12, while its midportion is provided with a horizontal slot 13 and a cylindrical opening 14 extending transversely to the length of the slot and intersecting its lower wall, as best shown in Figs. 3 and 4.

Slidably disposed within the slot is a bar 15, preferably of the "I" type in cross-section, as shown in Fig. 4, the underside of the bar carrying a row of teeth 16 disposed in crosswise relation to said bar. A shoulder 17 along the row of teeth on each side thereof serves to support the bar in its sliding movement within the slot 13.

Disposed within the opening 14 is a locking-pin 18, the pin being circular in cross-section but including a portion with two flat faces 19 and 20, the faces meeting at an angle and forming a wedge. The tip 21 of the wedge is adapted to fit between any two adjoining teeth 16 on the underside of bar 15. One end of the locking-pin

2

18 projects laterally out of the stationary member 10 and is equipped with a cross handle 22 passing diametrically through a hole in said pin, as best shown in Fig. 1.

5 A wire spring anchored at one end to the lower portion of member 10, as shown at 24, is coiled about the pin 18, its other end being looped over said handle 22, as shown at 25. This serves to bring about the engagement of the locking-pin with the teeth of bar 15, as best shown in Fig. 3.

10 Mounted upon one end of the bar 15 is a vertical bar 26 which at its upper portion includes two parallel ears or wings 27 for a pivotal support therebetween of a shank 28. The latter carries at its upper end an integrally-formed jaw 29 adapted for co-operation with jaw 12 already mentioned hereinabove. Numeral 30 indicates a bolt upon which the shank is fulcrumed. Mounted upon the lower end of the shank by means of a bolt 31 is a cam including a flat, circular base 32 and a peripheral ridge 33 projecting from the base at right angle thereto, the ridge forming an annular incline along a path such as is defined by the thread of a screw. This is best shown in Figs. 1 and 8.

25 A leafspring 34 attached to the body of the bar 26 by means of a screw 35 bears at its other end against said shank 28 at a point below the jaw 29 but above the fulcrum at 30. Under the tension of said spring the lower end of the shank bears against the top of the ridge, as shown in Figs. 1 and 8.

30 It will be noted that the length of the shank from its fulcrum at 30 to its lower end is about twice the distance from the fulcrum up. This, I wish to point out, is a very important feature as by reason of the leverage effected by this structure any object between the jaws of the vise will be held in a grip much more powerful than could be secured by the conventional screwdrives or cams.

35 A rod 36 projecting radially from the ridge 33 serves as a handle for the operation of the annular cam as a whole. A weight 37 at the end of the rod serves a purpose which will be described hereinbelow.

40 The species of my vise shown in Fig. 5 is provided with means of gripping pipes. The features adapted for that use do not interfere with the use of the vise for other purposes of which the vise is capable. The stationary member 38 including a base 39 for mounting the vise on a horizontal support is provided with a series of circular holes 40. The holes are graduated in size and open from each side of said member 38 into

a slot 41 which accommodates a sliding bar 42. The bar is in all respects made like bar 15 shown in Fig. 1 but has in its web portion 43 a series of holes 44, the individual holes corresponding in size to holes 40 in said stationary member 38.

Associated with a portion 22a of rod 22 which operates the locking pin 18 is a pivoted L-shaped prop 47. Normally the prop is in the position shown in dotted lines 47a. When turned in a counter-clockwise direction to the position shown in solid lines in Fig. 5 it will, by means of rod 22, cause the locking pin 18 to be disengaged from teeth 16 of bar 42 and will permit said bar to be moved freely back and forth within the slot 41. Numeral 45 indicates a pipe which is held within aligned holes 40 of member 38 and a hole 44 aligned with said holes 40. Numeral 46 indicates a jaw projecting from the stationary member 38.

The operation of the vise is quite obvious. Assuming that an object is to be clamped between the jaws of the vise, handle 22 is pressed down to disengage the locking pin 18 from the teeth of bar 15 and to permit the bar to be shifted longitudinally within slot 13 of member 10. This is done in order that jaw 29 may be moved outwardly from the opposed jaw 12 or towards it, as the case may be, to have the object fit between said jaws. When handle 22 is released, tip 24 of the wedge portion of the locking pin 18 will engage teeth 16 of the sliding bar 42 and lock said bar in place. Next, in order to secure a powerful grip on the object, jaw 29 is made to bear against it, said jaw being actuated by means of the annular cam. The cam is rotated about its axis by means of a handle 36, the inclined ridge 33 of the cam forcing shank 28, which is fulcrumed at 30, outwardly. As the shank is much longer than the distance from the fulcrum to said jaw 29, the leverage effected by the shank will result in the delivery of intense pressure at the face of the jaw 29 in the direction of the opposite jaw 12. Once the object has been clamped between the jaws, as above described, any jar of the vise such as may result from working on the object will cause the weight of the handle 36 to swing downwardly only to tighten the wedge of the ridge 33 against the shank 28 and thus to tighten the grip of the object between said jaws.

In case the object to be held in the vise is a pipe, it is the vise shown in Fig. 5 that may be best used for the purpose. The pipe, provided it is of a diameter somewhat smaller than one of the apertures 40 in the stationary member 38 of the vise, may be inserted in one of said apertures, as shown in the drawings, and through a corresponding hole 44 in the sliding bar 42. In order that the bar may move freely within the slot 41 in said member 38, prop 47 is swung to a position shown in solid lines in Fig. 5 where it will raise end 22a of rod 22, turning the locking pin 18 out of engagement with the teeth 16 of bar 42. Thereupon the annular cam already described is rotated to cause the upper jaw 29 to bear against the opposed jaw 46 and to cause a pull to be exerted outwardly upon said sliding bar 42. As a result a grip will be effected upon a pipe analogous to a grip between two jaws of a vise. One side of openings 40 will represent

one jaw; the opposite side of the hole 44 within the sliding bar will represent the equivalent of the opposed jaw.

It must be added that normally, unless this is prevented by the annular cam, jaw 29 is kept in a spaced relation to jaw 46 by means of a leaf spring 34.

It will be understood that some changes may be made in the structure of my vise without departing from the inventive principle disclosed herein.

What I, therefore, wish to claim is as follows:

1. A vise comprising a vertical stationary member having a jaw at the top, the member being provided with a horizontal slot below the level of said jaw, a sliding bar within the slot, the bar being provided with a row of teeth cut therein along its length, a locking pin within said stationary member, the pin being adapted for engagement with said teeth to prevent longitudinal movement of the bar, manual means for the operation of the locking pin; an upright plate mounted at one end of the bar, the plate being provided with a pair of upright flanges disposed parallel to each other, a lever pivoted upon a pin journaled within said flanges, the lever terminating at the top with a jaw opposed to the first-named jaw, a spring keeping the jaws in a normally spaced relation to each other, an annular cam mounted upon the lower end of the upright plate, the cam including a circular ridge following the thread of a screw and bearing against said lower end of the lever, and a handle projecting radially from the cam by means of which the cam may be rotated.

2. A vise comprising a vertical stationary member having a jaw at the top, the member being provided with a horizontal slot below the level of said jaw, a sliding bar within the slot, an upright plate mounted at one end of the bar, the plate being provided with a pair of flanges disposed parallel to each other, an upright lever pivoted upon a pin journaled within said flanges, the lever terminating at the top with a jaw opposed to the first-named jaw, a spring keeping the jaws in a normally spaced relation to each other, the sides of the stationary member being provided with a plurality of holes of graduated sizes and arranged in a horizontal line, the sliding bar being similarly provided with a series of holes of corresponding sizes for alignment, one by one, with the first-named holes, an annular cam mounted upon the lower end of the upright plate, the cam including a circular ridge following the thread of a screw and bearing against the lower end of the lever, and handle means to rotate the cam to cause the jaw upon the lever to bear against the opposed jaw and to exert a pull upon said sliding bar.

WILLIAM MILUS.
